UNITED STATES PATENT OFFICE.

H. CLAY BASCOM, OF TROY, NEW YORK.

DESIGN FOR A HEATING-STOVE.

SPECIFICATION forming part of Design No. 15,385, dated September 9, 1884.

Application filed June 17, 1884. Term of patent 7 years.

To all whom it may concern:

Be it known that I, H. CLAY BASCOM, a citizen of the United States, residing in the city of Troy, in the county of Rensselaer and State of New York, have invented and produced a new and original Design for Heating-Stoves, of which the following is a specification, reference being had to the accompanying cut, print, or engraving of a stove having 10 said design.

This invention embraces several new and distinct parts and combinations of parts, which go to make up the whole design, as shown in the aforesaid print and hereinafter specified.

15 One distinguishing feature of this design is the shape and ornamentation of the body portion, consisting of the top section, A, middle section, B, and base-section C.

The design for the circular upper section, 20 A, consists of the flat top surface, *a*, having a pipe-collar, *a'*, the convex border-molding *b*, having the ornaments *b'*, the overhanging rim *c*, the downwardly-conical part *d*, concavely-curved part *e*, and downwardly-tapering portion *f*, having the row of alternating ornaments *f' f''*.

The design for the middle circular section, B, consists of the downwardly-flaring top part, *g*, having the ornaments *g'*, the overhanging 30 rim *h*, the convexly-curved surface *i*, the mid-ring *j*, and the lower convexly-curved surface, *k*, having the ornaments *k'*.

The design for the base-section C consists of the shape and ornamentation of the register-ring *l*, quadrilateral top plate, *m*, having recessed rounded corners *m'*, the upright quadrilateral portion *n*, having the recessed corners *n'*, front door, *p*, and side panel, *p'*, and the quadrilateral bottom plate, *o*, having the 40 recessed rounded corners *o'*.

The design for the feed-door D consists of the convexly-curved trapezoidal panel *q*, having the border *r*, corner-rosettes *s*, and the

ornamentation consisting of the central ornament, *t*, quadrant ornament *u*, and the intermediate extensions, *v v'*. 45

The design for the legs consists of the convexly and concavely curved surface *w*, having the central ornament, *x*, quadrant ornaments *y*, intermediate ornaments, *y'*, and the border *z*. 50

The whole design embraces the shape and ornamentation of the sections A B C, door D, and the legs.

I claim as new— 55

1. In a design for a stove, the shape and ornamentation of the body portion, consisting of the sections A, B, and C, as set forth.

2. In a design for a stove, the shape and ornamentation of the upper section, A, consisting of the parts *a' b' b' c* and *d e f' f''*, as set forth. 60

3. In a design for a stove, the shape and ornamentation of the middle section, B, consisting of the parts *g' g', h, i, j*, and *k k'*, as set forth. 65

4. In a design for a stove, the shape and ornamentation of the base-section C, consisting of the parts *l, m' m', n' n', p p'*, and *o o'*, as set forth.

5. In a design for a stove, the shape and ornamentation of the door D, consisting of the parts *q r s t u v v'*, as set forth. 70

6. In a design for a stove, the shape and ornamentation of the legs, consisting of the parts *w x y y' z*, as described.

7. A design for a stove, consisting of the sections A B C, door D, and the legs, shaped and ornamented as set forth.

In testimony whereof I have set my hand, 80 in the presence of two subscribing witnesses, this 14th day of June, 1884.

H. CLAY BASCOM.
